UNITED STATES PATENT OFFICE.

ARNDT L. HAMMARBERG, OF YOUNGSTOWN, OHIO.

GAS-VALVE.

No. 856,252.

Specification of Letters Patent.

Patented June 11, 1907.

Application filed September 20, 1906. Serial No. 335,374.

To all whom it may concern:

Be it known that I, ARNDT L. HAMMARBERG, of Youngstown, in the county of Mahoning, State of Ohio, have invented a new and useful Gas-Valve, of which the following is a full, clear, and exact description, reference being had to the accompanying drawings, forming part of this specification, in which—

10 Figure 1 is a vertical sectional view illustrating my invention; Fig. 2 is a side elevation partially in section; Fig. 3 is a plan view partially in section on the line III—III of Fig. 1; Fig. 4 is an enlarged detail view 15 of one of the clamps by means of which the water-trough is secured around the valve-seat.

Like symbols of reference indicate like parts wherever they occur.

20 My invention relates to a water-cooled valve which, although it is specially adapted to the purpose of reversing the gas in a Siemens' regenerative furnace, it is also applicable to other furnace valves for furnaces 25 or hot blast stoves where it is desirable to retain a close even joint between the valve and its seat and to prevent the valve from warping or being otherwise injured by the action of the heat.

30 Heretofore it has been common to prevent injury to the valves and to insure a close joint between the valve and its seat by means of water-jackets consisting of closed cast-iron chambers or coils of wrought-iron 35 pipe set in the brick-work and through which water is caused to circulate, thus producing an internally cooled valve, or by water-seals which consist of an open trough into which the valve, in the shape of an inverted cup, seats itself, thus producing a 40 water-cooled and water-sealed joint. Water-jackets set in the masonry of the valve are objectionable for the reason that sediment, mud, and other impurities in the water are deposited in the jacket which, being 45 thus protected from the cooling action of the water soon lose their cooling properties, allowing the valves and other parts to warp and burn. The objections to a water-sealed 50 valve are that it is open to the gas in the gas-main and soon becomes clogged with soot and other impurities contained in the gas.

The object of my invention is to provide 55 water-cooling for valves by means of a

trough or conduit which, while it is at all times open for the removal of sediment, mud, and other impurities deposited by the water, it is also closed to the gas contained in the gas-mains.

The further object is to so construct the gas-mains as to permit the ready removal of the valves when it is desirable to do the same.

My invention therefore consists in the provision of externally cooled valve seats in which the action of the cooling water can at all times be readily controlled and observed and from which sediment and other deposits may be removed at any time without interfering with the action and operation of the valve.

It also consists in providing means whereby the elbow above the valve may be swung to one side thereby permitting the ready removal and replacement of the valve.

I will now describe my invention so that others skilled in the art may manufacture and use the same.

In the drawing *a* represents the gas-flue leading from the gas producer to the furnace; located in this flue in the usual manner and form is the sand-damper *b* and the valve *c* which serve to regulate the admission of the gas. Leading from the gas-flue *a* are two outlets formed by the nozzles *d*, *d'*, to which nozzles are secured the elbows *e*, *e'* by means of the hinges *e*² thus forming a hinge joint between the nozzle and the elbow. To the lower end of the elbows *e*, *e'* are attached the water-cooled valve-seats *f* which are in the form of annular troughs, the inner face *f'* of the trough forming the seat of the valve. These troughs have inclined bottoms or inner sides *f'* which permit the valve to seat itself easily and evenly when the valve is closed. Directly below the water-troughs *f* and fastened to them by hinge bolts *g* are the casings *h*, *h'*, open at top and bottom and having side outlets *k*, *k'* which communicate with the hoods *l* leading to the furnace flue *m*. These hoods *l* may be of the ordinary design. The casings *h*, *h'* are supported by the water-troughs *n*, *n'* which form the lower water-cooled valve-seats. These water-troughs *n*, *n'* are similar in design to the upper water-troughs *f*, *f'* excepting that a portion of the lower water-troughs extends through the bridge-wall *o* between the furnace flues *m* and stack flues *p*, and thus not

only serve as a water-cooled valve-seat but also serve to cool the bridge-wall *o* which, owing to its shape and position, is subject to a cutting and wearing heat. The water-troughs *n*, are preferably secured to the casings *h* by hook bolts *q*, one of which is shown in Fig. 4. Water is kept circulating in water-troughs *f*, *f'* and *n*, *n'* by suitable inlet and outlet water-pipes whereby the valve-seats are continually kept cool. In the position shown in the drawings the valve *r'* admits producer gas to the furnace and the valve *r* discharges the waste gases to the stack. By raising the valve *r'* to the upper valve seat and dropping the valve *r* to the lower valve-seat, the furnace is reversed. The valves may be operated by hand or by power as is desired.

When it is desired to inspect or to renew the valves *r* or *r'*, the valve *c* is first closed and the valves *r* or *r'* are raised to the upper valve seat, the bolts *g* and *s* are now unhooked and the elbow *e* is swung open, which allows the valve saucer to be dropped in the open. In this manner the valve can be easily or quickly renewed or inspected.

The advantages of my invention as hereinbefore stated, and described, will be appreciated by those skilled in the art.

Having thus described my invention, what

I claim and desire to secure by Letters Patent is:

1. In a gas-valve for gas-mains, the combination of a casing, a valve seat, and an externally open water-trough on the outer face 35 of said valve seat, the wall of the valve seat constituting the inner wall of the water-trough and forming a portion of the gas-main.

2. In a gas-valve for gas-mains, the combination of a casing, a valve, an upper valve seat, a lower valve seat, a water-trough on the outer face of each valve seat, said water-trough being open exteriorly and closed to the interior of the casing, the walls of the 45 valve seats constituting the inner walls of the water-troughs and forming portions of the gas-main.

3. In a gas-valve, the combination of a casing, an elbow, a valve-seat secured to the 50 lower portion of the elbow, and a hinged joint on the elbow whereby the elbow may be swung clear of the casing for the purpose of renewing the valve.

In testimony whereof, I have hereunto set 55 my hand.

ARNDT L. HAMMARBERG.
